J. B. BLOW

FIRE TRUCK APPARATUS

Filed Feb. 4, 1924

UNITED STATES PATENT OFFICE.

JACOB B. BLAW, OF ATLANTIC CITY, NEW JERSEY.

FIRE-TRUCK APPARATUS.

Application filed February 4, 1924. Serial No. 690,419.

To all whom it may concern:

Be it known that I, JACOB B. BLAW, a citizen of the United States, and resident of Atlantic City, county of Atlantic, and State 5 of New Jersey, have invented an Improvement in Fire-Truck Apparatus, of which the following is a specification.

An object of my invention is to provide a fire truck, preferably of the extension ladder type, with means whereby a plurality of separately supported adjustable fire hose nozzles may be attached for throwing streams of water in any desired direction, the truck sustaining the nozzles in various 15 positions of adjustment with the result that a large number of streams may be maintained upon the conflagration without the necessity of any continued handling of the nozzles by hosemen. This improvement is 20 not only useful where a large number of streams are required to be concentrated upon definite portions of the building on fire, but also in those cases where, owing to intense heat, a water screen is necessary to 25 protect the firemen and also the adjacent buildings facing the burning structure.

My object is further, to provide the truck with a water main having lateral openings for simultaneously supplying a number of 30 hose nozzles with water under pressure and simplifying the delivery of water to the nozzles, whereby an increase in efficiency is obtained in respect to speed of application 35 of the streams to the fire.

A further object of my invention is to 40 reduce the confusion and difficulties from too many lines of hose, where a large number of streams are necessary, this being possible by the use of one or more water-mains on the truck, from which short hose sections connect with the nozzles, whether attached 45 to the truck or otherwise, the water being supplied to the said main or mains on the truck by one or more hose lines leading from the fire engine or high pressure street plugs.

With these and other objects in view, my 50 invention consists of certain improvements in fire truck apparatus for efficiently delivering a plurality of water streams with a minimum requirement of manual labor and attention on the part of the firemen, all of which are fully set out hereinafter and more specifically defined in the claims.

The present invention is, in a measure, 55 an improvement upon the fire apparatus set out in my application Serial Number

680,094, filed December 12, 1923, in which I have shown a fire ladder truck provided with special fire nozzle supporting means adapted to be adjustably clamped to the 60 ladder and whereby the nozzle may be adjusted for directing the stream where needed and continue to operate without requiring the immediate attention of the firemen, the device being adapted for water tower effect 65 and for directing a plurality of streams simultaneously by employment of a plurality of similar fire nozzles and supports connected to a ladder, on or off the truck, as desired. 70

Referring to the drawings: Fig. 1 is a side elevation of an extension ladder truck having my improvements applied thereto; Fig. 2 is a transverse section of a portion of the same, taken on line 2—2 of Fig. 1; Fig. 3 75 is a plan view of the water main employed on the truck; Fig. 4 is a sectional view of a portion of one of the ladders having one of my improved fire hose nozzle holders attached thereto; and Fig. 5 is a plan view illustrating the fire hose in typical form for supplying water from different sources to the water main on the truck.

3 is the chassis or main frame of the truck which is shown as motor driven. The 85 chassis is provided with the usual pivoted extension ladder 4 having suitable means 5 for raising and lowering it as customary. The chassis is also provided with uprights 6 having transverse supporting rollers 7, one 90 above the other, for sustaining the several ladders 8, as more fully shown in Fig. 2. These uprights 6 are also conveniently provided with arms 6^a at their upper ends upon which ladders may be hung longitudinally 95 of the truck at each side, one of which, 9, being shown in position in Fig. 2. The general construction of the truck is immaterial to my invention, as any of the ladder trucks in general use are adapted for my improvements; and it will, therefore, be understood 100 that what I have illustrated is by way of example only and not as restricting my invention to any particular type of truck.

Arranged along the length of the chassis 105 3 is a water main 11, having at intervals lateral outlets 12 adapted for connection with hose couplings and also respectively provided with shut-off valves 13. This water main 11 is preferably secured to the 110 underside of the chassis by sustaining members 16, or in any other way desired; and

at one end, desirably the rear end, this main is provided with a plurality of inlet nozzles 14 also adapted to be connected with hose couplings and said inlet nozzles 14 also provided with shut-off valves 15, all of which is clearly indicated in Fig. 3. At the other end, the water main 11 is preferably branched, as at 11^a, reaching to the sides of the chassis and terminating in coupling nozzles 14^a also having shut-off valves 13^a. While the nozzles 14 are intended as inlets for the water from the fire engines or high pressure mains, nozzles 14^a may be employed for inlets or outlets as desired or as necessity may dictate.

In respect to supplying water to the main 11 on the trunk, I have shown, in Fig. 5, three sources of water supply. One of the nozzles 14 receives supply from a high pressure water system by hose line 36, whereas another of the nozzles 14 receives water from a hose section 32 which, in turn, receives a water supply from two lines of hose 34 and 35 leading to separate fire engines (not shown) and delivering into hose 32, by means of the Y coupling 33. The remaining nozzle 14 is shut off by valve 15 but may, if desired, be coupled to another source of water supply. As these hose lines are not directly connected with the fire hose nozzles 25 and hence do not have to be shifted, there is little need of them becoming entangled, objectionably overlapping, or obstructing the street.

The apparatus which has now been described is intended to bring the water supply to a common place of distribution, namely, at the truck. It is my purpose to provide fire hose nozzles 25 adjustably supported on the truck or ladders thereof and connected by short sections of fire hose 29 with the respective outlets 12 of the water main 11. In Fig. 1 provision is made for twelve fire nozzles arranged as in Fig. 2, for example, but where additional hose lines are available, more of the fire nozzles may be clamped to the ladders 4 by use of supporting devices, such as shown in Fig. 4. In practice, I have employed six additional such lines and fire nozzles and have found it convenient to employ twelve to eighteen streams from a single ladder truck and all set for continued operation without the necessity of manual control at any nozzle. Where the extension ladder 4 is raised, one or more of the nozzle supports of Fig. 4 may be applied so that the device may act as a water tower, the additional fire nozzles being secured to the uppermost of the horizontal ladders remaining. By enabling the streams to be directed and maintained on the fire in this manner, I am able to increase the efficiency of the fire department in that the firemen may nearly all be utilized in handling special streams which must be defi-

nitely shifted from place to place, and such work may be made more effective by using my invention to provide a water screen for their protection where necessary.

Referring now more particularly to the means shown for adjustably supporting the fire nozzles 25 upon or in connection with the truck and its ladders and which are more particularly shown in Figs. 2 and 4: 18 is a frame providing two leg portions spread apart and each having a suitable adjustable clamp 19 by which they may be fitted to and firmly take hold of the rungs 10 of a ladder, such as 9, and from which it projects at a more or less right angle, as shown in Fig. 80. Secured to the said frame 18, at its end most distant from the clamps 19, is a head 20 to which is hinged a strut 21 having at its free end an adjustable clamping jaw 22, also adapted to be clamped upon a rung of the ladder. This strut 21 may be adjustable by suitable sleeve screwing upon right and left hand threaded portions, as is clearly shown. In this manner, the frame 18 and the head 20 may be definitely positioned in attachment to the ladder. Pivoted in the head 20 is the yoke 23 which may be adjustable about an axis substantially parallel to the length of the ladder and at right angles to the frame 18 and in which its position of adjustment may be insured by a clamping screw 28. Hinged to the yoke 23 is a saddle 24 in which the fire nozzle 25 is clamped. The saddle 24 is provided with a curved segment 26 adjustable in the yoke 23 and adapted to be clamped against movement by a clamping screw 27. In this manner, the nozzle is universally supported and may be set at any angle desired. The nozzle 25 is coupled to one end of the short hose section 29 before referred to, said section being flexible so as to permit of any adjustment desired to the nozzle. In Fig. 1, there is shown six outlets 12 from the water main 11 which are all adapted for connection with an adjustable nozzle and support of the character illustrated in Figs. 2 and 4, the same being attached to the ladder 9 illustrated in Fig. 2, but not shown in Fig. 1. It will be understood that, if desired, the nozzle 25 may be disconnected from the saddle 24 and be manipulated by the firemen, in which case it would be free, as indicated in dotted lines at *x*; and it is also evident that one or more additional lengths of hose may be connected with the hose 29 to provide greater adjustability in the handling of the nozzle, such additional hose length being also indicated in the dotted portion.

It will also be understood that if it is desired to employ additional fire nozzles on the uppermost horizontal ladders 8, the same may be applied in a similar manner and may be considered as illustrated in Fig. 4, if the ladder 9 therein were assumed to be

one of the horizontal ladders 8 or even the extension ladder 4, if its extension capacity were not required. On the other hand, if a nozzle was attached in this manner to an extension ladder and the same was elevated, it is manifest that the nozzle would be elevated with it and might, in that position, be employed with the ladder as a water tower.

10 In addition to having capacity for attachment to the rungs of the ladders, these fire nozzles 25, together with their yokes 23, may be adjustably clamped to the hubs 30 secured to the chassis and in which they 15 may be adjustably clamped by clamping screws 31, as shown at the left hand side of Fig. 2. This capacity may be employed where the ladder 9 is required for other purposes. In practice, there would be one of 20 these yoke supporting hubs 30 for each one of the outlets 12 of the water main 11, and hence in the truck of Fig. 1, there would be ten of such nozzle supporting hubs, and consequently a capacity for ten separate 25 streams from these sources. In addition to these streams, further streams may be taken from the nozzles 14^a either in connection with the extension ladder or with any of the other ladders or, if preferred, in independent 30 manually employed fire nozzles. It will further be understood that if it is required that all of the fire nozzles shall be arranged at one side of the truck instead of on both sides, (Fig. 2), the yoke 23 shown 35 at the left hand side of Fig. 2 may be uncoupled from the hub 30 on that side and applied to the hub 30 on the opposite side of the truck or that where the supporting frames 18 are arranged on the ladder, and 40 in this way the entire ten nozzles may be fixedly attached to the truck and all playing streams from the same side thereof, such adjustability of the fire nozzles being possible in view of the flexible sections of 45 the hose 29 by which the nozzles are coupled with the outlets 12 of the water main.

It will be understood that by leaving the water supply to the longitudinal water main 11 on the truck and the taking off therefrom the various streams that are necessary by the laterally extending hose lines, great simplicity in reaching the nozzles is insured, and this is true whether the water main 11 on the truck is intended to supply the adjustably positioned nozzles attached to the truck or to supply separate hose lines leading to fire nozzles handled by the firemen, or for both of these purposes, and consequently not only is the system of supply to a common distribution simple and effective, but the distribution of the water from said place of distribution to the various fire nozzle is also exceedingly simple and not liable to material interference. It will also be seen that as all of the inlets and outlets to the

water main 11 are provided with independent valves, any nozzle may be shut off for any reason, such as not being used or in case of bursting of a hose length 29, the pressure in the main may be maintained and 70 the distribution of the water insured to the plurality of nozzles which may be required to be put into action.

I have shown the means of attaching the nozzles to the ladder rungs which I have 75 found excellently adapted for the conditions in practice, but I do not limit myself to the particular construction illustrated as the nozzles may be adjustably attached to the truck or ladders in any other suitable manner.

It will now be apparent that I have devised a novel and useful construction which embodies the features of advantage enumerated as desirable, and while I have in the present instance shown and described the preferred embodiment thereof which has been found in practice to give satisfactory and reliable results, it is to be understood that I do not restrict myself to the details, 85 as the same are susceptible of modification in various particulars without departing from the spirit or scope of the invention.

Having now described my invention, what I claim as new and desire to secure by Letters Patent is:

1. The combination with a truck of a water main arranged along the length thereof and provided with a plurality of lateral valved outlets at intervals apart opening to the atmosphere outside of the truck and said main also having an inlet for receiving water supply, a plurality of fire nozzles universally supported at the outside of the truck and spaced along its length at a distance 100 from the outer side thereof, said nozzles detachably positioned and arranged for throwing streams of water in all directions and from one side of the truck over the same to the other side thereof, means for clamping 105 the fire nozzles rigidly in their various positions of adjustment whereby a plurality of streams may be directed upon a fire occurring at either side of the truck and continued as to direction without immediate attention of firemen, and flexible hose sections arranged entirely at the outside of the truck and extending from the fire nozzles and detachably connected with the lateral outlets 110 of the water main.

2. The invention according to claim 1, wherein the truck is provided at its outer side with a ladder support and a ladder positioned thereon with its length arranged horizontally to bring the rungs thereof into vertical positions, and wherein further, the means for detachably positioning the respective fire nozzles upon the truck comprise a laterally projecting support having means for detachably gripping the vertical ladder 115 120 125 130

rungs and at the outer end having means for receiving and holding the fire nozzle.

3. A truck having a water main extending along its length at its underside and provided with an inlet and also with lateral valved outlets at intervals along its length, said outlets opening to the atmosphere outside of the truck, in combination with a plurality of flexible hose sections also outside of the truck and detachably secured to the outlets of the water main, said hose sections provided at their outer ends with fire nozzles, a plurality of nozzle clamps for sever-

ally holding the fire nozzles in directive positions, and a plurality of separate means 15 detachably connected to the outside of the truck for supporting the respective nozzle clamps at positions considerably extended from the sides of the truck and at an elevation whereby firemen standing upon the 20 ground may adjust the directive positions of the nozzles.

In testimony of which invention, I hereunto set my hand.

JACOB B. BLAW.
